UNITED STATES PATENT OFFICE.

BENJAMIN OTTO FANSLOW, OF LOS ANGELES, CALIFORNIA, ASSIGNOR, BY MESNE ASSIGNMENTS, TO POLYGRAPH DUPLICATING TYPEWRITER COMPANY, A CORPORATION OF NEW YORK.

PRINTING-MACHINE.

1,188,427.

Specification of Letters Patent. Patented June 27, 1916.

Application filed May 10, 1907. Serial No. 372,970.

To all whom it may concern:

Be it known that I, BENJAMIN O. FANSLOW, a citizen of the United States, residing at Los Angeles, in the county of Los Angeles and State of California, have invented certain new and useful Improvements in Printing-Machines, of which the following is a description.

This invention relates to printing machines, having reference more particularly to improvements in a printing machine heretofore invented by me wherein the printing from a type-bed, electroplate, or other composition is effected through the agency of a printing ribbon overlying the same and an impression roller rolling over the sheet of paper or other material on which the print is to be made placed above said ribbon, such machine constituting the subject-matter of Letters Patent #873,361, granted to me on the 10th day of December, 1907. The leading use to which such a machine is put is the production of multiple copies of letters; and the subject-matter of the present invention relates more particularly to a means in the nature of an addressing attachment for said machine, whereby successive letters, as they are printed, may be supplied with different addresses at the same time that the body of the letter is printed.

A further extension of the principle of the present invention, which I have also illustrated herein, consists in the addition of a device whereby the envelop may be printed simultaneously with the printing of each letter and its special address.

The invention will be readily understood when considered in connection with the accompanying drawings illustrating practical embodiments thereof and in which:

Figure 1 is a plan wherein part of the printing-ribbon is broken out of my improved printing machine equipped with an attachment for printing different addresses at the heads of the letters; Fig. 2 is a longitudinal, vertical section through the machine of Fig. 1; Fig. 3 is an end elevation corresponding to Fig. 1; Fig. 4 is a cross

section on the line 4—4 of Fig. 1, looking in the direction indicated by the arrows in Fig. 1; Fig. 5 is a detail plan of a portion of the type-carrying chain constituting an element of the addressing mechanism; Fig. 6 is an edge view of one of the links of said chain; Fig. 7 is a detail elevation of one of the types; Fig. 8 is a cross section of a link of the type-carrying chain, showing the type inserted therein; Fig. 9 is a plan of the machine equipped for addressing envelopes simultaneously with the printing of a complete letter; Fig. 10 is a cross section on the line 10—10 of Fig. 9, looking in the direction indicated by the arrows in Fig. 9; and Fig. 11 is a part longitudinal section of the machine on the line 11—11 of Fig. 9, viewed in the direction indicated by the arrows in Fig. 9.

Referring to the drawings, and first briefly describing the principal parts of the printing machine proper, such as are disclosed and claimed in my patent hereinabove referred to, 12 designates the horizontal stationary bed of the machine, herein shown as supporting a chase 13 of type, and provided with parallel low side-walls 14, the upper surfaces of which constitute tracks or ways for the ends of an impression-roller 15, which latter is journaled in bearings in a carriage 16, extending across the bed, said carriage having vertical ends 17 (Fig. 3) provided with rollers 18, which engage with the undercut grooves 19, formed in the lateral projections of the side-walls 14. On the axle 20 of the impression-roller 15 is a crank-handle 21, by turning which, in either a right or left hand direction, the impression-roller is caused to roll back and forth over the tracks 14. A printing-ribbon 22, of sufficient width to entirely cover the type-bed, is mounted at its opposite ends on rollers 23, journaled in the ends of the bed, which rollers are provided on one end with ratchet-disks 24, adapted to be engaged and turned, one tooth at a time, by pawls 25, mounted upon the carriage 16. Said pawls are secured to the carriage of the impre-

sion-roller as by screws 27, Figs. 1, 3 and 9, whereby the pawls may be alternately turned upwardly and out of operative position, as indicated at the right in Fig. 1, so that but one pawl will operate during the feed of the ribbon in one direction, the other pawl being thrown into operative position as soon as the ribbon has made a complete traverse over the bed-frame. The parts are so adjusted that the impression-roller 15, which is preferably rubber-surfaced, will have a yielding pressure on the ribbon 22 and, through the latter, on the type in the chase 13; so that an impression of the type will be distinctly printed, through the inking-ribbon 22, on the lower surface of a sheet of paper placed thereon, such as is indicated at 28, in Fig. 2, interposed between the impression-roller 15 and the printing-ribbon, when the cylinder is rolled over said sheet of paper.

Coming now more particularly to those parts and devices which constitute principally the subject-matter of the present invention, and referring first to the simpler form of the invention illustrated in Figs. 1 to 4, inclusive, a carrier 29, having the form of a hexagonal plate or block is shown mounted in a vertical plane transversely of the bed of the machine on a longitudinal shaft 30, said carrier projecting upward through a slot or opening 31, in the bed of the machine, to such an extent that its flat, marginal surfaces, when at their highest points, lie substantially in the horizontal plane of the upper face of the type-chase 13. Engaging the polygonal periphery of the carrier 29 is a chain, which may be endless, or of any required length adapted to carry the number of addresses represented by each link thereof, this chain being made up of a series of pivoted links 32 (Figs. 2, 3, 4, 5 and 6), each of which links constitutes a type-carrier or frame for the type constituting an address. The links 32 are made of substantially the same width as the width of the carrier 29, and are preferably, and in accordance with the present invention, constructed to removably and securely hold the type in the following manner. Each link is formed with one or more longitudinal slots 33, Fig. 5, the opposite margins whereof are turned upwardly at an angle, as shown at 34. The type 35, as shown more particularly in the detail view, Fig. 7, is formed with a pair of transverse converging grooves 26, on its under side, thereby leaving a depending dove-tailed projection 37 between said grooves; and by sliding the type endwise upon and between the turned-up flanges 34 of the link or type carrier 32, said turned-up flanges engage the grooves 36 of each of the types, while the dove-tailed projection 37 snugly fits the slot between and

beneath said flanges, all as clearly shown in the detail cross-sectional view, Fig. 8. This construction affords a very secure and rigid holder for the type, which, nevertheless, permits their easy application and removal; and, furthermore, it permits the bases 37 of the type to rest securely and squarely upon the polygonal edges of the carrier 29, as the links successively come into engagement with said edges under the turning of the shaft 30. When a line or row of type has been set up it may be secured against endwise displacement by tightly-fitting stops of rubber, or other suitable material inserted in the ends of the type-holder. The several links are connected by ordinary hinge-pintles 38, engaging eyes 32^a and hooks 32^b on meeting ends of the links, to accommodate which pintles the corners of the polygonal carrier are notched or recessed transversely, as shown at 29^a, in Fig. 4.

The addressing device thus constituted is automatically actuated to bring a fresh address into the printing plane on each to and fro movement of the impression-roller and its carriage by the mechanism next to be described. Depending from one side of the impression-roller carriage 16 is a bracket 39 (Figs. 2 and 3), to which are pivoted a pair of oppositely-projecting pawls 40. These pawls, at the limit of travel of the impression-roller carriage in each direction, engage ratchet-disks 41, which are fast on short shafts 42, Figs. 2, 3 and 4 and indicated in dotted lines in Figs. 1 and 9, journaled in bearings beneath the bed of the machine, which shafts 42 carry on their inner ends bevel-wheels 43, which mesh with bevel-pinions 44, on the opposite ends of the longitudinal shaft 30, carrying the chain-carrier 29. It will thus be seen that each time the impression-roller carriage 16 reaches the end of its travel, having overrun the chase 13 and the type-chain 32, carrying the addresses, said type-chain is moved through part of a revolution corresponding to the number of flat surfaces on the chain-carrier 29, thus presenting a new address at each such movement; so that all the attendant has to do is to supply a fresh sheet of paper properly positioned above the ribbon after each complete movement of the impression-roller.

Figs. 9 to 11 illustrate an extension of the mechanism herein last described to adapt the machine to print an envelop simultaneously with the printing of a letter. In this case, I provide on the other side of the longitudinal axis of the machine-bed another chain-carrier 45, similar in all respects to the carrier 29, said carrier 45 supporting a chain of links 46, similar in all respects to the links 32, supported by the carrier 29.

This carrier 45 is mounted on a short longitudinal shaft 47, journaled beneath the bed of the machine, which shaft is geared to the main longitudinal shaft 30, by spur-gears 48 5 and 49, on said shafts 47 and 30, respectively, and an intermediate idler-gear 50. In this arrangement, the ratchet-disks represented by 41^a, Figs. 9 and 10, are preferably located at diagonally opposite corners 10 of the bed-frame, and are geared to the shafts 30 and 47 by bevel-gear and pinion mechanism similar to that already described and clearly shown in the plan, Fig. 9. In this case, of course, the actuating-pawl 40 15 are mounted on opposite ends of the impression-roller carriage, respectively.

From the foregoing it will be seen that, by laying a sheet of paper upon the part 20 of the printing-ribbon 22, overlying the main type-bed and the addressing-chain 32, and by also laying an envelop face downwardly upon that part of the printing-ribbon overlying the envelop-addressing chain 46, and causing the impression-roller to roll 25 over both the sheet and the envelop, not only is a complete letter, including the address, printed at a single travel of the cylinder, but the address is likewise simultaneously printed upon the envelop.

Having thus described my invention, what I claim and desire to secure by Letters Patent is:

1. A multiple-copy printing machine having, in combination, a frame for supporting a composition, an impression-cylinder mounted for reciprocation and to travel over the composition, a rotatable form support, an endless form of composition adapted to have portions thereof moved into printing 35 position by said form support, and means associated with said impression-cylinder for moving said form support upon each movement of reciprocation of the cylinder.

2. In a machine for printing multiple 45 copies of letters with different addresses, the combination with a machine-frame adapted to hold a bed of type from which the body of the letter is printed, and a carriage carrying an impression-cylinder mounted to travel thereover, of an addressing attachment comprising a movable carrier mounted in said machine-frame, a series of type-plates supported and successively movable into printing position by said carrier, and means carried by said cylinder carriage for actuating said carrier at the 50 limits of travel of said cylinder carriage, substantially as described.

3. In a printing machine of the character 60 described, the combination with a machine-frame adapted to hold a bed of type, a printing-ribbon overlying the latter, and an impression-cylinder mounted to travel to and fro over said ribbon, of a rotatable type-

chain carrier having a polygonal periphery 65 mounted in the frame of said machine, a type-chain mounted on said carrier the links whereof are adapted to successively rest upon the periphery of said carrier as the latter is rotated and means associated with 70 the cylinder for moving said type-chain carrier at the end of each movement of the cylinder, substantially as described.

4. In a printing machine of the character described, the combination with a machine-frame adapted to hold a bed of type, a printing-ribbon overlying the latter, and a carriage containing an impression-cylinder mounted for reciprocation and to travel over said ribbon, of a rotatable type-chain carrier having a polygonal periphery mounted 75 in the frame of said machine, a type-chain mounted on said carrier, the links whereof are adapted to successively rest upon the periphery of said carrier as the latter is rotated, and means automatically actuated by said carriage during each movement of reciprocation of the latter for rotating said type-chain carrier, substantially as described. 80

5. In a printing machine of the character described, the combination with a machine-frame adapted to hold a bed of type, a printing-ribbon overlying the latter, and a carriage containing an impression-cylinder 90 mounted to travel over said ribbon, of a rotatable type-chain carrier having a polygonal periphery mounted in and transversely of the frame of said machine with the upper edge of said type-chain carrier 95 substantially in the plane of the type-bed, a type-chain mounted on said carrier the links whereof are adapted to support type, each of said links having substantially the area of each of the flat surfaces of said carrier and adapted to rest thereon, and means automatically actuated by said carriage upon each reciprocatory movement of the latter for rotating said type-chain carrier, substantially as described. 100

6. In a printing machine of the character described, the combination with a machine-frame adapted to hold a bed of type, a printing-ribbon overlying the latter, and a carriage containing an impression-cylinder 110 mounted to travel over said ribbon, of a shaft mounted longitudinally of and beneath said machine-frame, a type-chain carrier having a polygonal periphery mounted on said shaft and projecting across the 115 plane of the type-bed, a type-chain mounted on said carrier the links whereof have substantially the area of each of the flat surfaces of said carrier and are adapted to rest thereon, transversely-disposed shafts beneath and at each end of said machine-frame, respectively, coöperating gears on the inner ends of said transverse shafts and 120

the adjacent ends of said longitudinal shaft, respectively, ratchet-disks on the outer ends of said transverse shafts, and pawls carried by said carriage adapted to strike and actuate said ratchet-disks at the limits of movement of said carriage over the machine-frame, substantially as described.

7. In a machine for printing multiple copies of letters with different addresses, 10 and simultaneously printing envelopes therefor, a stationary flat bed of type, an inking-ribbon over said type from which the body of a letter is printed, said machine having an impression-roller mounted to travel upon 15 the paper laid upon the inking-ribbon, in combination with a letter-addressing attachment and an envelop-addressing attachment both mounted in the frame of said machine, and means for moving said attachments simultaneously with each reciprocation of the impression-roller, whereby to present different addresses successively in the printing plane, substantially as described.

25 8. In a machine for printing multiple copies of letters with different addresses and simultaneously printing envelopes therefor, the combination with a machine-frame adapted to hold a bed of type from which 30 the body of the letter is printed, and an impression-cylinder mounted to travel thereover, of letter-addressing and envelope-addressing attachments mounted in said machine-frame on opposite sides of the longitudinal median line of the latter, respectively, and means for automatically actuating both of said addressing attachments simultaneously with each reciprocation of the impression-cylinder whereby to present 35 different addresses successively in the printing plane, substantially as described.

9. A multiple-copy printing machine having, in combination, a form-carrying frame, a composition, composed of a plurality of 45 separated forms, mounted on said frame, inking means movable bodily over and coöperating with said composition, rotatable impression means movable bodily relatively to and coöperating successively with said 50 forms, and means to cause one of said forms to move in a plane parallel to the axis of the impression means upon each operation thereof.

10. In a printing machine, a frame adapted 55 to receive a form, impression means movable to and fro over the form and adapted to print at each backward and each forward stroke, and means for feeding and returning individual lines of type to and from the 60 form at each forward and each backward movement of the said impression means.

11. In a printing machine, a frame, a type bed adapted to receive a form, a roller carriage carrying an impression roller, means

for moving the impression roller to and fro 65 over the form and means for automatically and periodically feeding individual lines of type from the under-side of the type bed to the form at the backward and forward movement of the roller carriage.

70 12. In a printing machine a frame adapted to receive a form, a roller carriage movable to and fro over the printing surface and carrying an impression roller adapted to print at each backward and each forward 75 stroke and means controlled by said roller carriage for automatically and periodically feeding individual lines of type from the underside of the type bed to the form during the backward and also during the forward 80 movement of the roller carriage.

13. In a printing machine, a frame adapted to receive a form, impression means movable to and fro over the type surface and adapted to print at each forward and each 85 backward stroke, a carrying device for an inking ribbon, means for feeding and returning individual lines of type to and from the form during each forward and also during the backward stroke of the said impression means, and means controlled by the 90 said impression means for feeding the inking ribbon at each second stroke of the said impression means.

95 14. In a printing machine, a frame adapted to receive a form, impression means movable to and fro over the form, and means for feeding and returning individual lines of type to and from the form at each functional operation of said impression means.

100 15. In a printing machine of the character described, the combination with a machine frame adapted to hold a bed of type, an impression cylinder mounted for reciprocation and to travel over said bed of type, of a 105 rotatable type-chain carrier mounted in the frame of the machine, a type-chain adapted to have the links thereof successively moved into printing position by said carrier, and means associated with said impression cylinder for moving said type-chain carrier upon each movement of reciprocation of the cylinder.

115 16. A printing machine having, in combination, a form-carrying frame, a form of 120 composition on the frame, an endless form of composition adapted to have portions thereof successively brought into printing position, a rotatable impression roller movable bodily over and coöperating with said forms, advancing means for moving said endless form in a plane substantially parallel to the axis of said impression roller, and means for operating said advancing means upon each bodily movement of the impression roller.

125 17. A printing machine having, in combination, a type-bed, an impression roller

adapted to bodily travel thereover, a feeding member and having a polygonal periphery of flat surfaces formed with notches therein at the juncture of each pair of said surfaces,
5 an endless type-chain suspended on said feeding member and having its links of substantially the same area as said surfaces and provided with enlarged portions at the juncture of adjacent links thereof, said enlarged
10 portions of the chain being adapted to be

received in said notches whereby the links of the type-chain are properly presented and positioned successively.

In testimony that I claim the foregoing as my invention, I have hereunto subscribed 15 my name in the presence of two witnesses.

BENJAMIN OTTO FANSLOW.
